UNITED STATES PATENT OFFICE

FREELAND W. OSTROM, OF BRIDGEPORT, CONNECTICUT, ASSIGNOR TO THE WHEELER & WILSON MANUFACTURING COMPANY, OF SAME PLACE.

CUTTING MECHANISM FOR BUTTON-HOLE SEWING-MACHINES.

SPECIFICATION forming part of Letters Patent No. 430,786, dated June 24, 1890.

Application filed December 14, 1888. Serial No. 293,590. (No model.)

To all whom it may concern:

Be it known that I, FREELAND W. OSTROM, of Bridgeport, county of Fairfield, State of Connecticut, have invented an Improvement 5 in Cutting Mechanism for Button-Hole-Stitching Machines, of which the following description, in connection with the accompanying drawings, is a specification, like letters and figures on the drawings representing like parts.

10 This invention has for its object to improve the mechanism described in United States Patent No. 367,315, granted to me, dated July 26, 1887, to which reference may be had. In the patent therein described the adjustment 15 for the cutter-bar with relation to the cloth-clamp holding the cloth containing the button-hole to be stitched is obtained by means of eccentric bearings in which the cutter-bar reciprocates. In this my present invention, 20 instead of securing the blade or cutter directly to the lower end of the cutter-bar, I have provided the latter at its lower end with a web upon which is mounted an independent blade-holder to which the blade is attached, 25 the said blade-holder being made adjustable on the said web laterally with relation to the cutter-bar, so as to place the blade connected with the said holder in central position with 30 relation to the stitching constituting the sides of the button-hole.

Figure 1 is a partial side elevation of the forward part of a sewing-machine of well-known construction with my improvement added thereto; Fig. 2, a right-hand end elevation of the parts shown in Fig. 1. Fig. 3 shows the throat-plate detached. Fig. 4 is an under side view of the throat-plate. Fig. 5 shows an enlarged portion of the bar with the holder and plate attached thereto. Fig. 6 is 40 a detail showing the web, and Fig. 7 is a detail showing the blade with its hole to fit one of the studs.

Referring to the drawings, A represents the bed or cloth plate of the machine; A', part of the overhanging arm; A², the needle-bar actuating rock-shaft; A³, its arm; A⁴, a link; A⁵, a needle-bar; B, a rotary hook or device to engage the loop of needle-thread; b, a blade; C C', parts of a cloth-carrying clamp, the 50 parts so designated being common to the pat-

ent referred to, wherein they are designated by like letters.

The arm C' of the cloth-clamping mechanism has attached to its forward end the usual slotted frame or foot (marked a) through 55 which the needle a' descends when stitching the button-hole, the said foot resting upon the material laid upon the upper side of the member C of the cloth-clamp.

The throat-plate c of the machine, having 60 the needle-hole c' and a cutting-blade f and spring-plates c³ are all as in the patent referred to, where they are designated by like letters. Herein the bar d is provided at its lower end with a web or plate d', which, as 65 represented, is secured to the bar d by a screw d², a part of the web or plate entering a vertical slot at the lower end of the bar d. This web or plate, as represented, has at one side a groove 2, which receives in it a projection 70 3 of a holder e, the holder being secured to the said web by a screw 4, the shank of which is extended through a slot 5 (see Fig. 6) in the web d', so that the said holder may be adjusted laterally at right angles to the longitudinal center of the bar d when it is desired 75 to change the position of the blade b with relation to the opening in the foot a and with relation to the stitching constituting the sides of the button-hole, the stitching taking place 80 within the said foot a.

The holder, as represented herein, has a clamping-block d³, which is secured to the holder by means of a screw 6. The holder, as shown, has also two guiding-studs 7 8, one 85 of which enters a hole 9 of the blade b when the blade is applied to the holder.

The clamping-plate d³ is acted upon by the screw 6 when the latter is turned in it, thus serving to firmly secure the plate to the holder. 90 The web d', connected to the lower end of the cutter-bar exactly at right angles to the blade-holder and the attached blade, serves as a guide upon or along which the said blade-holder may be quickly moved in a straight 95 line. When it is desired to adjust the blade into central position, and when adjusting the position of the blade, it is not unclamped on the holder, but the blade-holder is simply loosened to be adjusted on the web in a straight 100

line at right angles to the length of the cutting-edge of the blade, the web preventing any twisting or turning aside of the blade-holder.

5 I claim—

In a button-hole-stitching machine, the combination, with a cloth-clamp, the vertically-reciprocating cutter-bar, and the web connected to its lower end, of a blade and independent blade-holder adjustably secured to the said web, the said blade-holder, with the blade connected thereto, being adjustable together laterally with relation to the said cutter-bar and to the longitudinal center of the opening in the cloth-clamp, thereby enabling the edge of the blade during its lateral adjustment to be maintained centrally with relation to the stitching constituting the sides of a button-hole, substantially as described.

In testimony whereof I have signed my name to this specification in the presence of two subscribing witnesses.

FREELAND W. OSTROM.
